SACHET CONTAINER

Paul H. Ganz, New York, N. Y.

Application September 11, 1935, Serial No. 40,049

10 Claims. (Cl. 132—78.5)

This invention relates in general to containers and in particular to containers adapted to hold sachet powder and is particularly adapted for use in connection with stored articles such as linens or wearing apparel to which it is desired to impart a fragrance.

While my invention has been shown as applied to sachet containers it is to be understood that as to certain phases thereof it may have other 10 uses.

Among the objects of my invention are the provision of a sachet container that will be rigid and form sustaining, so that the contents thereof are protected, and yet one that will freely permit the escape of the fragrance of the sachet powder contained therewithin, and further, a sachet container having an attractive appearance combined with the aforementioned desirable structural features.

20 For the attainment of these objects and such other objects as will hereinafter appear or be pointed out, I have shown one embodiment of my invention in the drawing, in which:—

Figure 1 is an elevational view of my invention 25 with certain hidden structural features indicated in dotted lines;

Figure 2 is a sectional view on the line 2—2 of Figure 1, looking in the direction of the arrows;

Figure 3 is a sectional view on the line 3—3 of 30 Figure 2, looking in the direction of the arrows; and

Figure 4 is an exploded view showing in separated form all of the parts of the sachet container except the outer covering and indicating 35 the manner of assembling the same by showing the parts in their relative positions of assembly, except, however, that they are spaced from each other instead of being in adjacency.

As will be observed on inspection of the drawing, I have shown my sachet container as comprising a pair of interfitting shells 10 and 12 of rigid material, and these, when assembled as shown in Figure 2, form a substantially spherical, hollow body. For purposes of interfitting they 45 may be conveniently made with interfitting flanges 14. Each shell is shown as provided with a plurality of openings 16 and 18, all of which are adapted to allow passage of the fragrance of a sachet bag 20, adapted to fit within the hollow

50 of the sections 10 and 12, through the outer shell. The sachet bag 20 is made of some foraminous material, such as gauze, so that it will surround the sachet powder indicated at 22 in Figure 2, and retain the same, while freely permitting the 55 odor thereof to pass through its walls. It will be

obvious that the properties of the material of which the sachet is made, must be such that it will perform these functions properly.

As clearly shown in Figure 4 the bag 20 may be formed from a flat piece of material the ends of which are drawn up about the sachet powder and brought together in a bunch 21, and the ends may then be held together in any suitable or preferred manner, such as by tying with thread.

In order to impart an attractive appearance to 10 my sachet container, and also in order to hold the two halves of the rigid shell 10 and 12 together, without however preventing escape of the perfume through opening 16, I apply outside of said rigid shell an outer covering 24 made by 15 winding fibrous material thereover. For this purpose I have found bundles of untwisted artificial silk fibres an excellent material. In applying this outer covering the sachet bag may be supported at its ends by inserting spindles into 20 the openings 18 and then rotating it so that the fibrous material may be laid thereon in any suitable or preferred manner.

One manner of applying the fibrous material is indicated in Figure 1, and involves passing the 25 fibres from one side of one spindle point 18 to the opposite side of the other spindle point 18, so that the fibres assume a direction inclined to the meridian of the sphere, 18 being taken as the poles. During the application of the thread the 30 ball may be considered as having two motions, one of relatively rapid rotation through an axis almost perpendicular to the axis passing through the poles, and the other a relatively slow one about said axis. When the desired amount of 35 fibres have been applied, the free ends may be secured in any suitable or preferred manner, such as by the application of cement, which may be transparent and colorless.

It is to be observed that due to all of the 40 fibres passing adjacent the poles 18, the latter will be built so that the container will assume an ellipsoidal conformation, and that due to the aforementioned inclination of the fibres to the meridian, where two layers are superposed the 45 fibres thereof cross each other at an angle, as indicated in Figure 1, thereby producing peculiar ornamental effects.

It will be understood that all manner of ornamental effects may be produced by the use of 50 different kinds of fibres, threads or yarns, and by the judicious use of color, and by various modes of application of the fibres, threads or yarns.

It will be observed from Figure 2, that while 55 the fibrous covering is shown as extending over

the openings 16, it does not cover the openings 18, this being necessarily so where these openings are used as spindle supports, but where other methods of winding are used they may also be covered. If openings 18 are left uncovered, they will naturally exude the internal perfume more freely, but even if they are covered by material such as described, they, as well as openings 16 will still serve to emit a sufficient amount of perfume.

It is to be understood that the disclosure herein is not intended to be limiting in any sense but is by way of illustration only, and that my invention may be embodied in many other forms, as will be obvious to those skilled in the art, without departing from the spirit thereof as called for by the language of the appended claims.

Having thus described my invention and illustrated its use, what I claim as new and desire to secure by Letters Patent, is:—

1. A container for sachet powder or the like, comprising a rigid, hollow shell, provided with perforations leading from the exterior to the interior, a sachet unit within the hollow of said shell, said unit comprising a mass of sachet powder surrounded by an envelope of foraminous material, and a covering of fibrous material surrounding said shell on the outside thereof and serving to beautify the container without preventing the escape of odors from the sachet unit.

2. A container for sachet powder or the like, comprising a rigid, hollow shell, provided with perforations leading from the exterior to the interior, a sachet unit within the hollow of said shell, said unit comprising a mass of sachet powder surrounded by an envelope of foraminous material, and a covering of fibres laid between two polar points of said shell on the outside thereof, and substantially surrounding the same and serving to beautify the container without preventing the escape of odors from the sachet unit.

3. A container for sachet powder or the like, comprising a rigid, hollow shell, provided with perforations leading from the exterior to the interior, a sachet unit within the hollow of said shell, said unit comprising a mass of sachet powder surrounded by an envelope of foraminous material, and a covering of substantially parallel fibres surrounding said shell on the outside thereof and serving to beautify the container without preventing the escape of odors from the sachet unit.

4. A container for sachet powder or the like, comprising a rigid, hollow shell containing perfume-emitting material and provided with per-

forations leading from the exterior to the interior, and a covering of fibres laid between the two poles of said shell on the outside thereof and substantially surrounding the same and serving to beautify the container without preventing the escape of odors from the sachet unit.

5. In a sachet container, a rigid, hollow shell comprising two complementary members adapted for assembly so as to form a closed hollow container, vent openings in said members, a sachet bag within said shell, and means for holding said members of the shell in assembled relation and for partially obstructing said vents.

6. In a sachet container, a rigid hollow shell comprising two complementary members adapted for assembly so as to form a closed hollow container, vent openings in said members, a sachet bag within said shell, and an outer covering for said shell serving to hold the members thereof in assembled relation without preventing the emission of perfume through the vents.

7. In a sachet container, a rigid hollow shell comprising two complementary members adapted for assembly so as to form a closed hollow container, vent openings in said members, a sachet bag within said shell, and an outer covering of fibrous material for said shell, covering substantially the entire outer surface thereof, and serving to hold the members of said shell in assembled relation.

8. In a sachet container, a hollow shell comprising a plurality of sections adapted for assembly so as to form a closed hollow container, vent openings in said members, a sachet bag within said shell, and means for holding said members of the shell in assembled relation and for partially obstructing said vents.

9. In a sachet container, a hollow shell comprising a plurality of sections adapted for assembly so as to form a closed hollow container, means in the walls of said container for permitting the escape of perfume from the interior to the exterior, perfume-emitting material within said shell, and means for holding said members of the shell in assembled relation.

10. In a sachet container, a hollow shell comprising a plurality of sections adapted for assembly so as to form a closed hollow container, means in the walls of said container for permitting the escape of perfume from the interior to the exterior, perfume-emitting material within said shell, and means in the form of a covering for holding said members of the shell in assembled relation.
